UNITED STATES PATENT OFFICE.

HARRY HAMILTON RICHARDSON, OF BEAVERFALLS, PENNSYLVANIA,
ASSIGNOR TO AMERICA COMPANY, OF ROCKFORD, ILLINOIS, A COR-
PORATION OF ILLINOIS.

FISH-LINE REEL.

No. 795,648.

Specification of Letters Patent.

Patented July 25, 1905.

Application filed August 29, 1904. Serial No. 222,573.

To all whom it may concern:

Be it known that I, HARRY HAMILTON RICHARDSON, a citizen of the United States, residing at Beaverfalls, in the county of Beaver and State of Pennsylvania, have invented certain new and useful Improvements in Fish-Line Reels, of which the following is a specification.

The object of this invention is to equip a reel with a spooling attachment in order that the line may be uniformly laid on the spool and made movable out of the path of the line in casting, so as not to interfere therewith.

In the accompanying drawings, Figure 1 is an end elevation of my improved fish-line reel, with a portion of the casing broken away. Fig. 2 is a plan view of the same, in which the spooling device is shown thrown out in dotted lines. Fig. 3 is a side elevation. Fig. 4 is an inner face representation of the casing, showing the arrangement of the gearing. Fig. 5 is a section on dotted line *a*, Fig. 3.

The heads 1 and 2 are connected by the rods 3. A cap or casing 4 has a connection with the head 2. A spool 5 is supported by the head 1 and casing 4 and has a small toothed pinion 6 connected to it. A larger toothed wheel 7 is supported by the casing and meshes with the pinion 6 and is rotated by a handle connection 8. A curved plate 9 has a connection with two of the rods 3 and is used to form a connection with the fishing-rod in the usual manner. A bracket 10 is secured to the curved plate 9 and has two perforated ears 11.

A frame is composed of the lower bar 12, two ends 13, and a central depending lug 14. The lug 14 is located between the ears 11 and has a pivotal connection therewith. This lug has two flattened surfaces 15, against which a spring-rod 16 is adapted to bear for a purpose to appear hereinafter. The bar 12 has a rib 17 extending in its lengthwise direction and along its upper surface. A shaft 18 is supported by the ends 13 of the frame and to which is secured a toothed wheel 19. This shaft is provided with double threads 20, right and left. A clamp 21 is supported by the shaft and is provided with the usual dog engagement with the threads of the shaft. The clamp has a depending projection 22, provided with a grooved way 29, which receives the rib 17, thereby forming a sliding connec-

tion between the clamp and frame. The clamp has two fingers 23 extending from it, each supporting a ball 24. An intermediate toothed wheel 25 is supported by the casing in a manner that it may move radially from the toothed wheel 7, with which it is adapted to engage. The support for this intermediate toothed wheel extends through the casing and has a projection 28 on the outside of the casing. A spring 26 bears against the support for the intermediate toothed wheel 25 and holds the intermediate toothed wheel out of engagement with the main driving toothed wheel 7.

From one of the ends 13 of the frame extends a pin 27. When the spooling mechanism is in operative position, the chain of gears will be meshed, as shown in solid lines, Fig. 1, in which the intermediate toothed wheel 25 is held in mesh with the main toothed wheel 7 by the pin 27, pressing against the projection 28.

The spring-rod 16, resting against the flattened surface 15, holds the fingers 23 upright, at the same time holding the gear-train in mesh, so that by manipulating the handle the spool is rotated and the fingers moved back and forth in the lengthwise direction of the shaft 18, carrying the fish-line located between the fingers back and forth in the lengthwise direction of the spool.

The balls 24 hold the fish-line between the fingers; but the spring action of the fingers allows the balls to separate sufficiently to permit the passage of the fish-line in releasing it from between the fingers.

By turning the frame down into the position shown in dotted lines, Figs. 1 and 2, the gear-train will be broken by moving the toothed wheel 19 from the intermediate toothed wheel 25 and permitting the spring 26 to move the intermediate toothed wheel out of mesh with the main toothed wheel 7 in order that the spool may turn with the least resistance—for instance, in making a cast.

I claim as my invention—

1. A fish-line reel provided with a line-guide, the line-guide having two fingers held normally closed at their free ends.

2. A fish-line reel comprising two ends, a spool supported by the ends, gears for rotating the spool, a line-guide capable of a bodily movement in the lengthwise direction of the

spool, a toothed wheel for imparting movement to the line-guide, and an intermediate toothed wheel meshing with the gears for rotating the spool and imparting motion to the line-guide, the intermediate toothed wheel and the gear rotating the line-guide shaft capable of disengagement.

3. A fish-line reel comprising two ends, a spool supported by the ends, gears for rotating the spool, a line-guide capable of a bodily movement in the lengthwise direction of the spool, a toothed wheel for imparting movement to the line-guide, and an intermediate toothed wheel meshing with the gears for rotating the spool and imparting motion to the line-guide, the gear for imparting movement to the line-guide capable of disengagement with the intermediate wheel, and the intermediate wheel capable of disengagement with the gear for rotating the spool.

4. A fish-line reel comprising two ends, a spool supported by the ends, gears for rotating the spool, a line-guide capable of a bodily movement in the lengthwise direction of the spool, a toothed wheel for imparting movement to the line-guide, and an intermediate toothed wheel meshing with the gears for rotating the spool and imparting motion to the line-guide, the toothed wheel for imparting movement to the line-guide capable of a rocking movement to disengage it from the intermediate toothed wheel.

5. A fish-line reel comprising two ends, a spool supported by the ends, gears for rotating the spool, a line-guide capable of a bodily movement to the lengthwise direction of the spool, a toothed wheel for imparting movement to the line-guide, and an intermediate toothed wheel meshing with the gears for rotating the spool and imparting motion to the line-guide, the toothed wheel capable of a rocking movement to disengage it from the intermediate toothed wheel, and the intermediate toothed wheel capable of disengagement with the gear for rotating the spool.

6. A fish-line reel provided with a plate for attachment to the rod and a line-guide movably supported by the plate and capable of a movement at right angles to the length of the spool.

7. A fish-line reel provided with a plate for attachment to the rod, a line-guide pivotally supported by the plate and capable of a movement at right angles to the length of the spool.

8. A fish-line reel provided with a frame, a movable connection between the frame and reel, a shaft supported by the frame, a line-guide movable by the shaft and means for rotating the shaft.

HARRY HAMILTON RICHARDSON.
